US00D815367S

(12) **United States Design Patent** (10) Patent No.: **US D815,367 S**
(45) Date of Patent: **** Apr. 10, 2018**

(54) **RACING PIGEON FOOT RING**

(71) Applicant: **Shu-Hui Kao**, Taichung (TW)

(72) Inventor: **Shu-Hui Kao**, Taichung (TW)

(**) Term: **15 Years**

(21) Appl. No.: **29/571,501**

(22) Filed: **Jul. 19, 2016**

(51) LOC (11) Cl. **30-08**

(52) U.S. Cl.

USPC **D30/155**; D30/199

(58) **Field of Classification Search**

USPC D30/155, 199, 144–146, 151–153; 119/856, 858, 859, 860, 863, 865, 654, 119/712–714, 716, 720–726, 762, 763, 119/792, 816, 818, 850, 853, 174, 855, 119/862, 760, 789, 796, 815, 821; D11/2, 3, 4, 26, 5–25, 27–39, 131, 131.1, D11/133, 140, 155, 157, 93, 79, 80, D11/81–83, 86, 40–44, 94, 200, 201, 106, D11/114–116, 99, 220; 40/304, 300, 665, 40/640, 633, 726, 776, 617; 63/3, 3.1, 63/3.2, 5, 15.1–15.4, 15.45, 15.5, 15.6, 63/15.65, 15.7, 26–28, 1.11, 1.13–1.17, 63/5.1, 6, 7, 12, 15, 21, 33, 40, 41, 23, 63/14.1, 18–20, 11; D10/30–32, 111, 98, D10/70, 78, 104.1; D24/211, 167; D28/41; D23/366, 367; D8/383, 349, D8/394, 395, 396; D6/332, 468; D21/683; D5/45, 46, 7, 13; D29/120.1, D29/100, 101.5; D2/609, 627, 614, 628, D2/624, 632, 894; D26/11, 26, 113–118; D20/10, 22, 27, 40, 42, 11; D9/434, 428/690, 359/516; 2/232, 22, 468, 338; 424/411; 600/38, 301; 24/180, 625, 188, 24/662, 647; 439/352; 206/347; 362/103, 104, 216, 335, 108; 283/72, 74, 283/75, 103, 105, 106, 449; 229/72, 92,

(57) **CLAIM**

The ornamental design for a racing pigeon foot ring, as shown and described.

DESCRIPTION

FIG. 1 is a perspective view of a racing pigeon foot ring, showing my new design;

FIG. 2 is another perspective view thereof;

FIG. 3 is a front view thereof;

FIG. 4 is rear front view thereof;

FIG. 5 is a left side view thereof;

FIG. 6 is a right side view thereof;

FIG. 7 is a top view thereof;

FIG. 8 is a bottom view thereof; and,

FIG. 9 is an operational perspective view thereof showing a gate of the racing pigeon foot ring opened.

The elements depicted in broken line represent unclaimed features of the racing pigeon foot ring and form no part of the claimed design.

1 Claim, 9 Drawing Sheets
